UNITED STATES PATENT OFFICE.

JOHN F. O'CONNOR, OF CHICAGO, ILLINOIS, ASSIGNOR TO WILLIAM H. MINER, OF CHAZY, NEW YORK.

DRAFT-RIGGING FOR RAILWAY-CARS.

1,203,247.

Specification of Letter's Patent.

Patented Oct. 31, 1916.

Application filed October 22, 1914. Serial No. 867,948.

To all whom it may concern:

Be it known that I, JOHN F. O'CONNOR, a citizen of the United States, residing at Chicago, in the county of Cook and State of Illinois, have invented a certain new and useful Improvement in Draft-Rigging for Railway-Cars, of which the following is a full, clear, concise, and exact description, reference being had to the accompanying drawings, forming a part of this specification.

My invention relates to improvements in draft rigging for railway cars.

The object of my invention is to provide a draft rigging of simple construction and efficient operation.

In the drawings forming a part of the specification, Figure 1 is a side elevation, partly in vertical longitudinal section of a draft rigging embodying my invention. Fig. 2 is a plan view, partly in horizontal section on line 2—2 of Fig. 1. Fig. 3 is a cross section taken on line 3—3 of Fig. 1. Fig. 4 is a front end view of the draft gear. Fig. 5 is a cross section taken on line 5—5 of Fig. 1. Fig. 6 is an end view of wedge. Fig. 7 is an end view of a roller retaining sleeve. Fig. 8 is a perspective view of one of the friction shoes.

Referring to the drawings, the numerals 9—9 indicate draft members or parts of the car frame to which the draft rigging is applied, 10—10 the front stop members, 11—11 the rear stop members, and 12 the draw bar slidably engaged to a draft yoke 13 by means of the key 14 passing through longitudinally extended slots 15—15 in the lateral plates 16—16 of the yoke head 17, the said key 14 extending at its ends through the longitudinally extended slots 18—18 in the front stop members 10 and adjacent parts of the draft members 9. Within the yoke is mounted the front follower 20 and the draft gear 21 comprising a friction shell 22 and friction elements 23 and spring elements 24 within the shell. The shell is provided at its rear end with a preferably integral plate 25 and laterally extended shoulders 26, adapted to engage the rear stop members and hold the shell against rearward movement in buffing action of the gear. The shell is preferably provided with upper and lower flattened faces 27—27 respectively, the same being preferably formed intermediate the ends of the shell by a pair

of longitudinally extended spaced apart ribs 270—270. The friction mechanism comprises a wedge 28, coöperating with three frictional shoes 29, each shoe having an outer friction face 30, concave in longitudinal section and convex in transverse section, see Figs. 2 and 3. These shoes slide upon correspondingly curved friction faces 31 on the interior of the shell. Each face 31 is convex in longitudinal section and concave in transverse section. These faces 31 are so arranged that ribs 131 are formed therebetween by which the shoes 29 are guided in their longitudinal movements. The wedge 28 is cloverleaf shaped at its outer end and has wedging faces 32, one for each friction shoe, there being an anti-friction roller 33 interposed between each wedging face of the wedge and the adjacent anti-friction roller seat 34, with which each friction shoe is provided on its inner face. A roller retaining sleeve 35 is slidably mounted upon the connecting bolt 36, the connecting bolt passing through the parts 80 within the shell and having its head 37 received within a forwardly opening recess 38 in the wedge and being provided with a nut 39 received within a rearwardly opening recess 40 provided in the rear plate 25 of the shell 22. The roller retaining sleeve 35 is provided with a forwardly extended flange 41 engaging the anti-friction rollers and is rearwardly provided with a boss 42 surrounding the aperture 43, through which 75 the connecting bolt passes, there being a preliminary spring 45 seated against said sleeve and about the boss thereof at its forward end, the said preliminary spring being rearwardly seated about a boss 46 provided upon 80 the movable spring seat 47, which is likewise mounted upon the connecting bolt 36. The said spring seat 46 engages against the rear ends of the friction shoes and forms the forward seat for the spring members 100 24 of the gear, the said spring members preferably comprising an outer spring 48 and an inner spring 49 nested therein. The said springs 48 and 49 are rearwardly seated against the rear inner end of the 105 shell 22. In the embodiment of my invention, illustrated in the accompanying drawings, there is a roll of preferably about 15° to each friction shoe in its movement from normal position to its position when the 110 gear is under full compression, that is, as the wedge moves rearwardly on rearward

movement of the draw bar, the angle of thrust is comparatively acute, on account of the fact that the pressure transmitted from the wedge to the shoes through the anti-friction rolls is transmitted at a point forwardly of the narrowest diameter of the curved internal friction faces of the shell. As the wedge moves rearwardly exerting its spreading pressure through the anti-friction rollers upon the shoes, and the rearward movement of the shoes is resisted by the pressure of the spring members transmitted through the movable spring seat, the angle of thrust becomes greater and the frictional resistance constantly greater, until on full compression of the parts, the line of pressure from the wedge through the shoes extends outwardly to the friction shell, substantially at the point of its smallest diameter. Thus a graded and increasing resistance to compression is provided. The spring 45, hereinbefore for convenience designated a preliminary spring, exerts a forward pressure against the roller retaining sleeve, which in turn holds the anti-friction rollers in proper position during the roll of the curved shoes in their longitudinal movement within the shell. Thus my invention provides a draft gear in which a light compression resisting action is provided upon initial movement, the compression resisting power being increased during the stroke of the gear until a very high compression resisting capacity is afforded at the finish of the stroke.

Another feature of my improvements resides in the fact that as the wedge 28 moves inwardly, the rollers move toward the apex thereof and the inward travel of the shoes 40 29 is accelerated as they move along the gradually contracting mouth formed by the three curved friction shell surfaces 31.

I claim:

1. In a draft gear, a shell, friction shoes, and a wedge within the shell, springs associated and aligned with the friction shoes and contained within the shell, the shell being provided with a longitudinally curved friction face adapted to be engaged by the shoes.
2. In a draft gear, in combination, a shell, a wedge, a set of circularly arranged friction shoes and springs within the shell, the friction shoes having outer longitudinally curved friction faces, the shell having similarly curved interior friction faces engaging the shoes, the friction faces of the shell being arranged substantially circularly around the axis thereof.
3. In a draft gear, in combination, a shell, springs, friction shoes and a wedge within the shell, the shell being integrally provided with a longitudinally curved friction face,

the shoes being provided with similarly curved friction faces engaging therewith, 65 the angle of thrust from the wedge to the friction shoes gradually increasing during the inward movement of the friction shoes and wedge within the shell.

4. In a draft gear, in combination, a shell, 70 springs, friction shoes, a wedge within the shell, and anti-friction rollers directly interposed between said shoes and said wedge, the shell being provided with a longitudinally curved friction face, the shoes being 75 provided with similarly curved friction faces, the friction shoes having a rolling movement upon the friction face of the shell on rearward movement of the wedge in reference to the shell. 80

5. In a draft gear, in combination, a shell, springs, friction shoes and a wedge within the shell, the shell being provided with a longitudinally curved friction face, the friction shoes having similarly curved friction 85 faces engaging therewith, whereby the thrust of the wedge upon the shoes becomes increasingly direct as the shoes and wedge move inwardly in reference to the shell.

6. In a draft gear, in combination, a shell, 90 friction shoes, a wedge, springs, anti-friction rollers between the shoes and wedge and an anti-friction roller retainer sleeve within the shell, a connecting bolt passing through said sleeve and a spring seated against said 95 sleeve to hold the same in engagement against the anti-friction rollers.

7. In a draft gear, having a shell, friction shoes, a wedge and anti-friction rollers within the shell, a sleeve and a spring, the 100 sleeve engaging the anti-friction rollers to hold the same in position between the wedge and friction shoes, the spring being seated against said sleeve.

8. In a draft gear, the combination with 105 a friction shell, friction shoes, wedge, main spring, and anti-friction rollers mounted between the wedge and shoes, of a roller retaining sleeve engaging said anti-friction rollers, and a spring located within the 110 shoes and in engagement with said sleeve.

9. In a draft gear, in combination, a shell, friction shoes, a wedge and springs within the shell, anti-friction rollers between the wedge and friction shoes, a spring seat engaging the friction shoes and held against the same by the spring, a roller retaining sleeve engaging said rollers, and a further spring mounted between said spring seat and the roller retainer to hold the same in 120 engagement against the rollers. 115
